UNITED STATES PATENT OFFICE.

JOHN B. O'CONNOR, OF AURORA, ILLINOIS, ASSIGNOR TO LYON METALLIC MANUFACTURING COMPANY, OF AURORA, ILLINOIS, A CORPORATION OF ILLINOIS.

LOCKER-LATCH.

1,183,902.

Specification of Letters Patent. Patented May 23, 1916.

Application filed December 17, 1915. Serial No. 67,320.

To all whom it may concern:

Be it known that I, JOHN B. O'CONNOR, a citizen of the United States, residing at Aurora, in the county of Kane and State 5 of Illinois, have invented a certain new and useful Improvement in Locker-Latches, of which the following is a specification.

My invention relates to lockers and cabinets of the general type in which there is 10 a door hinged to the structure and provided with mechanism for locking the door in closed position.

My invention is particularly useful in connection with steel lockers of the class 15 used in club dressing rooms, factories, and elsewhere.

My present invention is concerned more particularly with the door handle and what may be referred to generally as the locking 20 mechanism, although my invention is not necessarily confined to that type of locking mechanism in which a key lock or combination lock is employed.

I have chosen to illustrate the invention 25 in connection with a present commercial steel locker, and while I have shown, incidentally, a special form of reinforcement for the door, I do not herein claim such reinforced construction, as this forms the 30 subject of a separate application filed by me December 31, 1915, Serial Number 69,535.

The object of my present invention is to provide locking mechanism which will automatically take hold when the door is 35 simply pushed closed and will automatically release by merely exerting a pull upon the door handle.

More specifically, it is my purpose to provide a vertically sliding latch bar located 40 on the inside of the door and adapted to move to operative position under the action of gravity, and a lever handle on the outside of the door fulcrumed near its upper end and normally lying substantially parallel 45 to the face of the door and automatically lifting the latch bar when an outward pull is exerted upon the handle.

Another object of the invention is to provide means for locking the bar in operative 50 position by mechanism located entirely on the inside of the door, the door being imperforate except for the key-hole and having no rivet heads or other fastening devices penetrating to the outside of the door.

Another object of the invention is to pro-

vide simple and effective means for preventing the door from being pried open.

I accomplish my objects by the mechanism illustrated in the accompanying drawings, in which—

Figure 1 is a front elevation, and Fig. 2 is a side elevation of a set of lockers embodying my invention. In each view a portion of the wall is broken away to reveal certain details of internal construction. 60 Fig. 3 is a perspective view looking at the inside of the door and showing the latching and locking mechanism. Fig. 4 is a perspective view somewhat similar to Fig. 3 which shows the particular manner of 65 mounting the latching and locking mechanism when used in connection with the special reinforced construction previously mentioned. Fig. 5 is a fragmentary detail in perspective showing the co-operation of 70 the latch bar and its stationary keeper. Fig. 6 is a view looking toward the back of the door and showing the latching and locking mechanism illustrated in Fig. 3. Fig. 7 is a 75 sectional elevation on the line 7—7, Fig. 80 Fig. 8 is a sectional elevation on the line 8—8, Fig. 6. Fig. 9 is a perspective view of the latch bar and mechanism which operates the same. Fig. 10 is a perspective view of the fulcrum plate which is mounted on the 85 outside of the door and supports the lever handle or door pull.

Similar numerals refer to similar parts throughout the several views.

In the drawings, the stationary part of 90 the locker is indicated in general by the reference numeral 1 and the door by the reference numeral 2. The construction of these parts, so far as my present invention is concerned, may be greatly varied without departing from the spirit of the invention, 95 but in the form shown, the angle iron 3 forms that portion of the door frame which comes adjacent to the vertical edge of the door remote from the hinges 4.

The door 2 has a marginal flange 5 which extends inward and comes adjacent to the angle iron 3. The latch bar 6, which is shown separately in Fig. 9, has a number of elongated slots 7, which extend longitudinally of the bar and receive headed pins 8 which are fastened to flange 5 in such position as to hold the bar in sliding contact with the inside surface of said flange. A number of latches 10 are riveted or other-

wise rigidly fastened to bar 6 and provided with hooked ends which drop over and engage the cross extensions 11^a of the keepers 11. Said keepers are riveted or otherwise 5 securely fastened to the inside of the angle iron 3 adjacent to the vertical edge thereof and in the preferred form have a special configuration which is perhaps best illustrated in Fig. 5. In this preferred form 10 each keeper has a base 11^b which is fastened to the angle iron and a standard 11^c extending therefrom parallel and adjacent to the outer surface of the door flange 5. The cross extension 11^a extends from the end of 15 the standard across the door flange and is engaged by the hooked end of the latch. A terminal flange 11^d projects at right angles to the cross extension 11^a so as to engage the inner side (or closely approach the inner 20 side) of the latch. As a result of this construction it is impossible to force the door open by inserting a jimmy or other prying tool, for the flange 11^d prevents the latch from being forced laterally away from 25 the keeper.

From the foregoing it will be seen that the latch bar is slidingly mounted upon the inside of the flange 5 and is provided with a plurality of latches which when lowered 30 drop over and engage and are engaged by keepers rigidly mounted on the stationary part of the locker. These parts move freely in a vertical direction and hence gravity tends to move the parts into latching or 35 acting position when the door is closed. The inner ends of the latches 10 are rounded so as to automatically ride over the keepers as the door is closing. The latch bar is lifted by means of a reversing lever 13 which is longitudinally slotted at one extremity to receive the pin 14 projecting from the lug 15 rigidly fastened to the inside of the latch bar. Said lever 13 is fulcrumed between its ends upon a pin 17 40 carried by a plate 18 fastened to the inside of the door. Said lever is connected at its inner end by a link 20 to the horizontal arm 21 of the lever handle. The handle proper consists of a depending arm 22 which 45 is preferably formed integral with the arm 21 and normally extends downward substantially parallel to the front of the door as shown, for example, in Fig. 7. The handle is supported upon a pin 23 carried by 50 the ears 24 of the fulcrum plate 25, said plate being shown separately in Fig. 10.

A lock 29 is secured to the plate 18 and is operated by a key which enters through a hole 30 formed in the door as shown in 55 Fig. 4. This lock has a bolt 28 which when projected engages said reversing lever and holds it in locked position. According to the best practice the lock 29 and the fulcrum pin 17 are fastened merely to plate 60 18 and the plate itself is afterward spot-

welded or otherwise fastened to the back of the door. This is of important advantage because it enables the door to present an imperforate surface at the front except where the key and the door lever pass 70 through. Consequently, it is practically impossible for any one to tamper with the mechanism or remove any of the parts or put them out of order. In fact nothing appears from the front except the lever handle and the key hole barrel and boss and there is nothing to afford a clew to either the shape, location or construction of the operating and locking mechanism. It is also desirable, for the same reason, to fasten 75 the fulcrum plate in the manner shown. This plate is of cast metal and has pins 25^a formed on the back, as best shown in Figs. 7 and 10. These pass through suitable apertures in the door and in the plate 18 and 80 when riveted over at the inner end hold the parts securely together and yet are invisible from the front.

In operation, the latch bar is normally held by gravity in lower-most position. As 90 the door swings shut the latches automatically ride over the keepers 11 and finally drop automatically into acting position. When it is desired to open the door, all that is necessary, is to pull on the lever handle 95 22, the pull serving the double purpose of lifting the latches and, when these are released, swinging the door to open position. A simple pull is the most natural movement 100 to impart to any handle, but with most handles it is necessary to turn the handle to release the latching mechanism and the pull simply opens the door after the latching mechanism is released. With my construction, however, the first half inch or so of 105 the movement of the door handle is devoted to releasing the latch and the balance of the movement, in the same direction, is effective for swinging the door. No conscious lifting or turning movement is required of 110 the operator and it may be said, therefore, that the action required of the operator is of the simplest possible form. If it is desired to lock the parts after they become 115 latched it is simply necessary to turn the key in the lock, which projects the bolt 28, which in turn prevents the lever 13 from rotating and holds the door securely locked.

Having thus described my invention, what I claim as new, and desire to secure by Letters Patent is:—

1. A locker having a door hinged thereto, a gravity operated, vertically slidable latching element mounted on the inside of the door, a lever handle fulcrumed upon the 125 door upon the outside thereof, said handle hanging down substantially parallel to the door and having an arm passing through the door to the inside thereof, and a reversing lever pivoted between its ends to the inside 130

of the door, said reversing lever being connected at one end to the latching element and at the other end to the inner end of the handle, whereby a pull upon said handle 5 perpendicularly to the surface of the door lifts said latching element.

2. A locker having a door hinged thereto, a plurality of keepers fastened to the locker adjacent to the door, latches for engaging 10 said keepers, a gravity operated latch bar vertically slideable upon said door and having said latches fastened thereto, a fulcrum plate fastened to the outside of the door, a lever handle hanging down in front 15 of the door approximately parallel thereto and being pivoted at its upper end to said fulcrum plate, on the outside of the door, the lever handle having an arm passing through an aperture in the door, and a reversing lever pivoted between its ends to the 20 inside of the door, and articulately connected at one end to the inner end of the lever handle and at the other end to said latch bar, whereby an outward pull upon the 25 handle perpendicularly away from the door lifts said latches.

3. The combination with a locker and hinged locker door, of a flange located at the edge of the door opposite to the hinges 30 and extending inwardly from the face of the door, a keeper fastened to the door frame adjacent to the flange, said keeper having a portion extending horizontally inward parallel to the door flange, thence laterally 35 across the inner edge of the flange to form a cross extension, a latch slideable vertically upon the door and adapted to drop over and engage said cross extension, and means for raising and lowering said latch. 40

4. The combination with a locker and hinged locker door, of a flange located at the edge of the door opposite to the hinges and extending inwardly from the face of the door, a keeper fastened to the door frame adjacent 45 to the flange, said keeper having a portion

extending horizontally inward parallel to the door flange, thence laterally across the inner edge of the flange to form a cross extension, thence horizontally inward thereby forming a terminal flange, a latch slideable 50 vertically upon the door and adapted to drop over and engage the cross extension of said keeper, the nose of the latch thereupon lying adjacent to the said terminal flange, and means for raising and lowering said 55 latch.

5. In a locker, the combination of a door, a vertically movable, gravity operated latching element, a reversing lever pivoted to the inside of the door and connected at one end 60 to said latching element for raising it, a handle depending from a pivot located on the outside of said door said handle being connected to said reversing lever for operating it, a lock having a bolt adapted to pass 65 beneath the end of the reversing lever opposite to the end where said lever is connected to said latching element, said lock being located on the inside of the door and the door being apertured opposite to the key-hole of the lock for receiving the key, where- 70 by the lock may be operated.

6. A locker having a sheet metal door, a flat sheet metal plate parallel to and in contact with the back of the door and fastened 75 thereto, a latching element slidably mounted upon said door, a lever on the back of said plate, said lever being connected to said latching element for operating it, a pivot supporting said lever, said pivot being sup- 80 ported solely by said plate, a pendant door pull pivoted at its upper end to the door and connected to said lever for operating it, and a lock located upon the back of the plate and supported solely by said plate for prevent- 85 ing the movement of said lever.

In witness whereof, I have hereunto subscribed my name.

JOHN B. O'CONNOR.
